(57) **CLAIM**

The ornamental design for an electric scooter as shown and described.

DESCRIPTION

FIG. 1 is a top, front and right side perspective view of an electric scooter showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2; and,

FIG. 11 is an enlarged view of portion 11 in FIG. 6.

The evenly spaced broken lines immediately adjacent to the claim depict the bounds of the claimed design, while all other evenly spaced broken lines are directed to environment.

The unevenly dashed broken lines illustrate the boundary of the enlarged views and form no part of the claimed design.

1 Claim, 11 Drawing Sheets
